(57) **CLAIM**

I claim the ornamental design for a steering wheel cover, as shown and described.

DESCRIPTION

FIG. 1 is a top front isometric view of a steering wheel cover in accordance with a first embodiment of the present design. FIG. 2 is a front elevation view of the steering wheel cover of FIG. 1. The rear elevation view is a mirror image of the front elevation view.

FIG. 3 is a left side elevation view of the steering wheel cover of FIG. 1. The right side elevation view is a mirror image of the left side elevation view.

FIG. 4 is a top plan view of the steering wheel cover of FIG. 1. The bottom plan view is a mirror image of the top plan view.

FIG. 5 is a top front isometric view of a steering wheel cover in accordance with a second embodiment of the present design.

FIG. 6 is a front elevation view of the steering wheel cover of FIG. 5. The rear elevation view is a mirror image of the front elevation view.

FIG. 7 is a left side elevation view of the steering wheel cover of FIG. 5. The right side elevation view is a mirror image of the left side elevation view.

FIG. 8 is a top plan view of the steering wheel cover of FIG. 5; and,

FIG. 9 is bottom plan view of the steering wheel cover of FIG. 5.

The broken lines illustrate stitch lines of the steering wheel cover that form no part of the claimed design.
